UNITED STATES PATENT OFFICE.

CLARA B. SIMPSON, OF WINNETKA, ILLINOIS.

FASTENING DEVICE.

1,295,623.

Specification of Letters Patent.

Patented Feb. 25, 1919.

Application filed November 18, 1918. Serial No. 262,919.

To all whom it may concern:

Be it known that I, CLARA B. SIMPSON, a citizen of the United States, and resident of Winnetka, in the county of Cook and 5 State of Illinois, have invented certain new and useful Improvements in Fastening Devices, of which the following is a specification.

This invention relates to fastening devices 10 or hooks to be used in connection with garments, gloves, and other lines in which two parts are to be connected.

Hooks now generally in use comprise a member bent or doubled back on itself in a 15 manner to have parts in engagement with each other for receiving and releasably retaining an associated eye member. Such hooks, in addition to being rather thick, are easily ruined when subjected to a compressive 20 action occasioned, for example, when the goods to which the hooks are applied are passed through a wringer. When such hooks, therefore, are flattened out, as a result of the compressive action, said hooks 25 no longer will receive or retain associated eye members. On the other hand, the hooks are rendered absolutely useless.

Accordingly, one object of my invention is to provide a hook for garments or the like 30 which will not be rendered useless when subjected to a compressive action.

Another object is to provide a simple, durable and relatively flat hook adapted to meet successfully the requirements for the 35 intended uses.

The invention is illustrated on the accompanying sheet of drawings, in which—

Figures 1, 2 and 3, respectively, are a plan view, and side and end elevations of my 40 hook;

Fig. 4 is a plan view of an associated eye member;

Fig. 5 is a plan view of the eye and hook in hooked relationship; and,

Fig. 6 is a view showing the hook and eye applied to two associated members which are to be connected.

The various novel features of the invention will be apparent from the following description and drawings and will be particularly pointed out in the appended claims.

Referring to the figures of the drawings, it will be noted that I have provided a fastening device comprising a member of 55 resilient material and including a frame portion 10 and a tongue 11 which is adapted

to engage a complementary member, such as an eye 12, for receiving and releasably retaining the latter in a locked or hooked relationship with the tongue and frame, as 60 shown in Fig. 5. The frame portion 10 and tongue 11 lie substantially in a single plane, thereby providing a relatively flat hook. The plane in which the frame portion 10 and tongue 11 lie is transverse to the plane 65 in which the tongue is yieldably movable. The frame portion 10, as shown, has one of its sides 13 formed integrally with the tongue 11, the opposite side 14 of the frame being releasably engaged by the tongue to 70 form a barrier therefor. The tongue side 13 of the frame is elongated to provide an extended torsionally resilient axis of tongue movement.

Normally the tongue engages the frame 75 side 14 with considerable pressure which must be overcome when applying and withdrawing the eye member. Preferably the outer end of the tongue is curved over the frame to facilitate the operation of the parts 80 and to avoid any protruding edges which might prove an annoyance. It will be noted that the tongue is narrower than the loop or eye 12, and that accordingly it is a simple matter to apply the latter to the hook. In 85 placing the hook and eye in locking relationship, the eye is drawn under the tongue 11 and between the latter and the frame side 14, temporarily springing the tongue out of engagement with the frame side 14, causing 90 the torsional twist in the frame side 13 to be increased and likewise the stored energy increased. As soon as the eye 12 is drawn inwardly beyond the frame side 14, it becomes releasably locked, as shown in Fig. 95 5. In this position, it will be noted that parts of the eye rest in depressions 15 in the frame side 13, which depressions receive turns of thread 16 to prevent shifting of the frame and also making it possible 100 for the hook and eye to lie in the same plane. The frame side 14 also may be provided with depressions 17 and the eye 12 with depressions 18 for the reception of turns of thread to prevent shifting of the members 105 in question. The hook and eye may be separated in a reverse manner from that of the application of same, the tongue 11 temporarily being forced out of engagement with the frame side 14.

In Fig. 6, I have shown my hook and eye applied to two parts which are to be con-

2
nected together or fastened. The hook and eye may be applied to garments of various description and arranged at any desired angle to meet the special needs. An eye member is not essential, for any suitable apertured member which will coöperate with the hook will be satisfactory.

It will be observed that compressive action exerted upon this flat hook will not damage it in any manner whatsoever; if anything, such action will improve the hook, whereas all forms of hooks used for garments and the like are collapsed or ruined when they are pressed, such, for example, as in passing through a wringer.

It is my intention to cover all modifications of the invention as set forth in the following claims.

I claim:

- 20 1. A fastening device comprising a member of resilient material and including a frame portion and a tongue adapted to engage a complementary member, said frame portion and tongue lying substantially in a single plane that is transverse to the plane of movement of the tongue, said frame portion having one side integral with the tongue and an opposite side coöoperating with the tongue to form a barrier therefor, the tongue side of the frame being elongated to provide an extended torsionally resilient axis of tongue movement.
- 25 2. A fastening device comprising a member of resilient material and including a frame portion and a tongue adapted to engage a complementary member, said frame portion and tongue lying substantially in a single plane that is transverse to the plane of movement of the tongue, said frame portion having one side integral with the tongue
- 30 3. A fastening device comprising a member of resilient material and including a frame portion and a tongue adapted to engage a complementary member, said frame portion and tongue lying substantially in a single plane that is transverse to the plane of movement of the tongue, said frame portion having one side integral with the tongue
- 35 4. A fastening device comprising a member of resilient material and including a frame portion and a tongue adapted to engage a complementary member, said frame portion and tongue lying substantially in a single plane that is transverse to the plane of movement of the tongue, the tongue side of the frame being elongated to provide an extended torsionally resilient axis of tongue movement, the tongue and complementary fastening member being connected by a continuous relative movement in one direction.
- 40 5. A fastening device comprising a frame portion and a tongue portion, the latter engaging the former as the result of torsional action extended over a relatively long axis.
- 45 6. A fastening device comprising a frame portion and a tongue portion, the latter engaging the former as the result of torsional action, the frame and tongue portions lying substantially in the same plane.

and an opposite side coöoperating with the tongue to form a barrier therefor, the tongue side of the frame being elongated to provide an extended torsionally resilient axis of tongue movement, the tongue being narrower than the associated complementary member.

3. A fastening device comprising a member including a frame portion and a tongue adapted to receive a complementary member, said frame portion having one side integral with the tongue and an opposite side coöoperating with the tongue to form a barrier therefor, the tongue side of the frame being elongated to provide an extended torsionally resilient axis of tongue movement.

4. A fastening device comprising a member including a frame portion and a tongue adapted to receive a complementary member, said frame portion having one side integral with the tongue and an opposite side coöoperating with the tongue to form a barrier therefor, the tongue side of the frame being elongated to provide an extended torsionally resilient axis of tongue movement, the tongue and complementary fastening member being connected by a continuous relative movement in one direction.

5. A fastening device comprising a frame portion and a tongue portion, the latter engaging the former as the result of torsional action extended over a relatively long axis.

6. A fastening device comprising a frame portion and a tongue portion, the latter engaging the former as the result of torsional action, the frame and tongue portions lying substantially in the same plane.

Signed at Winnetka, Illinois, this 12th day of November, 1918.

CLARA B. SIMPSON.
